METHOD OF AND APPARATUS FOR LASTING BOOTS AND SHOES.

1,326,112.

Specification of Letters Patent. Patented Dec. 23, 1919.

Application filed June 24, 1916. Serial No. 105,682.

To all whom it may concern:

Be it known that I, WILLIAM A. STUBBS, a citizen of the United States, residing at Winthrop, in the county of Suffolk and State of Massachusetts, have invented new and useful Improvements in Methods of and Apparatus for Lasting Boots and Shoes, of which the following is a specification.

This invention relates to the manufacture of boots and shoes that have stiffening members, and deals especially with the treating of such stiffening members. Most boots and shoes have counter-stiffeners and toe boxes, although some are made without toe boxes. If the stiffening members are stiff before they are incorporated into the shoes they must be treated, prior to the lasting operation, to render them limp enough to be lasted easily. I am aware that it has been proposed to make box toes by using absorbent stiffening members and impregnating or coating them, just prior to the lasting operation, with a stiffening compound in a fluid state, but in most cases the stiffening members are so prepared, or are made of such material, that they require softening prior to lasting.

My present invention contemplates broadly the operation of treating a shoe stiffener from the inside of the pulled-over or lasted shoe while the latter is upon a last. Such treatment may be a softening treatment or a stiffening treatment, according to the condition of the stiffening member prior to the treatment. For example, a "turned" shoe that has a relatively limp toe box would be more easily turned than one having a relatively stiff box, and it would be within the scope of this invention to last a shoe with a toe box made of absorbent but untreated material, and to apply a stiffening substance in fluid form to the latter after the shoe has been turned and while it is upon a last. But if the stiffener be stiff before it is incorporated into the shoe a softening treatment would be necessary, and hence my invention contemplates the feeding of a softening fluid to the stiffener while the latter is in the shoe and while the shoe is in a pulled-over or lasted condition upon a last. Such feeding of fluid, in either case, is made possible by using a last that has one or more internal ducts arranged to carry the fluid to the stiffening member or members. If a softening

fluid is needed steam or hot air, depending upon the character of the substance to be softened, could be fed through such ducts. Every last is provided with a jackpost cavity in its ankle portion, and accordingly the duct or ducts are arranged to have communication with such cavity. The fluid would be fed into the jackpost cavity, and the ducts are arranged in communication with such cavity and extend to points adjacent the heel stiffener or toe stiffener or both, according to the disposition of stiffening members in the shoe. A pulled-over or lasted shoe may therefore be steamed or otherwise heated internally, in which case the heating fluid would reach the stiffening member or members without having to pass through the upper and would be for this reason more effective than if it were directed against the exterior of the shoe.

The invention further contemplates an apparatus for feeding fluid into the jackpost cavity of the last, which apparatus may be used in conjunction with or independently of a toe steamer. In the event of using it in conjunction with a toe steamer, a fluid may be fed through the last and emitted inside the shoe while at the same time the toe portion of the last may be heated externally by the toe steamer. In this respect the invention embodies devices for utilizing the motion of the shoe toward and from the toe steamer to control the feeding of steam to the latter and to control the feeding of the fluid that is fed into the jackpost cavity of the last.

The fundamental idea of providing the last with internal ducts is capable of being embodied in lasts that have removable instep portions but that are otherwise unitary, and in lasts that have relatively movable heel-parts and foreparts.

Referring to the accompanying drawings:

Figure 1 represents a longitudinal section of a hinged last embodying the present invention.

Fig. 2 represents a plan view thereof.

Fig. 3 represents a section through the structure intersected by line 3-3 of Fig. 1.

Fig. 4 represents a longitudinal section through a last that has a removable instep portion but that is otherwise a one-piece last, embodying the present invention. In this figure the last is shown mounted upon a tu-

bular supporting member through which the heating medium may be fed into the jackpost cavity.

Fig. 5 represents an elevation showing a hinged last similar to that shown by Fig. 1, a pulled-over shoe thereon, and heating apparatus including a toe steamer, means for feeding a heating medium to the last, and valve mechanism for controlling the feeding of the heating medium to the interior of the last and for controlling the feeding of steam to the toe steamer.

Fig. 6 represents an end elevation of the apparatus shown by Fig. 5, as viewed from right to left.

Fig. 7 represents a sectional view through the valve structure intersected by line 7-7 of Fig. 6.

Fig. 8 represents a view of the same structure as that shown by Fig. 7 but showing the parts in a different relation.

Fig. 9 is a sectional view, on a larger scale, of the duct joint included in Fig. 1.

Fig. 10 is a sectional view through the structure intersected by line 10-10 of Fig. 5, looking down.

Fig. 11 is a section through the structure intersected by line 11-11 of Fig. 5.

The same reference characters indicate the same parts wherever they occur.

The two-part last shown by Figs. 1, 2 and 5 includes a forepart 12, heel-part 13, and jointed means connecting said parts so that the latter are capable of relative movement.

In the present instance the jointed connecting means is a simple hinge indicated as a whole at 14. In this respect the last is well known. It is customary to provide such a last with a spring or locking means adapted to keep the forepart and heel-part in the relation shown, which is the co-operative relation for lasting, but for the present purposes it is not necessary to illustrate any spring or locking means, and I have therefore omitted the latter to avoid undue complication of the drawings. The usual jackpost bushing is indicated at 15, and is arranged in the ankle portion of the last. This bushing provides a cavity into which a heating medium may be fed and from which it may be conducted through internal ducts in the last to the points where it is most desirable and necessary.

The heel portion is provided with a hollow metallic member 16 into which the heating medium is conducted by ducts or passageways formed in the heel-part. These ducts or passageways, and also all other ducts and passageways hereinafter described, are preferably lined with metal tubing to protect the wood of the last, as much as possible, from the warping effect of heat and moisture. The tubular lining members through which the heating medium is conducted from the jackpost cavity to the hol-

low member 16 are indicated at 17, 17. The inner ends of these ducts register with elongated holes 18 formed in the bushing 15. The reason for elongating the holes 18 is to maintain communication between the ducts and the jackpost cavity in case the jackpost bushing should be moved endwise by the pressure that is put upon the last by a heel-ing machine or sole-laying machine. The hollow member 16 is substantially U-shaped, as shown by Fig. 2, and its outer surface conforms to the surface of the counter portion of the last. The last is rabbeted for the reception of the member 16, and the latter is set in so that its outer surface will lie flush with the counter surface of the last. The outer side of the member 16 is provided with emission ports 19, and there may be as many such ports as desired, and they may be arranged wherever desired. The member 16 is substantially coextensive with the counter stiffeners with which shoes are ordinarily provided, and the steam or other heating medium that is emitted from the ports 19 may reach the counter stiffener close to the pulled-over edge 20 of the heel-part.

If it is desired to emit a heating medium in the toe portion of a pulled-over or lasted shoe, the last may be provided with another duct or ducts having communication with the jackpost cavity. As shown by Figs. 1 and 2, a metal bushing or lining member 21 is set into the toe portion of the last. The last is preferably bored from the sole to form the cavity for such bushing, and the opening thus left in the bottom of the last may be closed by a wooden plug such as that indicated at 22. The cavity provided by the bushing affords means of communication between a main duct and a large number of distributing ducts. These ducts are provided, in the present instance, by tubular metal lining members 23 and 24, the member 23 constituting the main duct and the members 24 being the distributing ducts. The latter are arranged in substantially radial relation in the toe portion, as shown by Fig. 2, and all have communication with the cavity of the bushing 21. The main duct 23 cannot extend without interruption to the jackpost cavity in the form shown by Fig. 1, because the heel-part and forepart have angular movement relatively to each other. For this reason the heel-part is provided with a tubular lining member 23' that is arranged to register with the member 23 in the forepart when the forepart and heel-part are in co-operative relation for lasting. A substantially tight joint between the members 23 and 23' can be made by forming the meeting ends thereof with co-operative frusto-conical surfaces as shown by Fig. 9. Such joint is indicated as a whole at 24* and is substantially coincident with the abutting surfaces of the forepart and heel-part. The

frusto-conical formation of the tubular members causes the latter to become centered relatively to each other as the forepart and heel-part are moved into the relation shown.

5 The last 25 shown by Fig. 4 is provided with substantially the same elements as the hinged last shown by Figs. 1, 2 and 5, but inasmuch as there is no division between the forepart and heel-part of the last 25, the 10 bore for the main duct 23 has to be begun at the back of the heel. This bore is made before the jackpost bushing is inserted, and the portion that is at the rear of said bushing is closed by a wooden plug 38. Inasmuch as the essentially new elements of the 15 last 25 are the same as those shown in Fig. 1, the same reference numerals are used to indicate them.

It will be understood, of course, that the 20 number and disposition of the distributing ducts 24 in the toe part may be varied at will. Fig. 4 includes a tubular supporting member 26 the upper end of which is adapted to go into the jackpost bushing.

25 This member has an external frusto-conical portion 27 adapted to fit tightly in the mouth of the bushing to form a substantially tight joint. The member 26 is adapted to conduct steam or other heating medium

30 into the last from a source of supply. Figs. 5 and 6 show a steam pipe 28 which for present purposes may be regarded as the source of supply. For reasons that will appear in due course, a flexible tube 29 is connect-

35 ed to supply pipe 28 and is coupled to a metal pipe 30. Pipe 30 is affixed to a block 31, and said block is arranged upon a bench 32. A swinging joint is indicated as a whole at 33 in Figs. 5 and 6. In Fig. 6 the axis

40 of the joint is indicated by broken line $x-x$, and in Fig. 5 the center of the joint is indicated at x' . The essential details of this joint are shown by Figs. 7 and 8. The stationary member of the joint is indicated at

45 34, and the oscillatory element is indicated at 35. The lower end of the supporting member 26 is fitted into the member 35, and communication between the stationary member 34 and the member 26 is afforded by ports

50 36 and 37. These ports are arranged to register with each other, as shown by Fig. 7, when the member 26 is in an upright position, as shown by Fig. 4 and as shown by solid lines in Fig. 5; but the supporting

55 member 26 is capable of swinging to the angular position shown by dotted lines in Fig. 5 and shown also by Fig. 8, in which position the port 37 is out of register with port 36. The members 34 and 35 thus con-

60 stitute a valve by which communication between the last and the source of supply is opened and closed according to the position of the supporting member 26.

In practice this device may be used as

follows. Assuming that the necessary elements of a shoe are assembled upon a last of the character hereinbefore described, with the upper pulled over preparatory to lasting, the laster would mount the last upon the member 26 while the latter is in the

65 angular position represented by dotted lines in Fig. 5. Having so mounted the last with the pulled-over shoe thereon, the laster would swing the member 26 to the upright

70 position to open communication between the last and source of supply from which the heating medium is fed. The last may be

75 left in the position shown by Fig. 5 as long as may be necessary to heat the stiffening members of the shoe, and in the meantime

80 the laster may be performing a lasting operation on another shoe. As each lasted shoe

85 is set aside the laster may remove the last and pulled-over shoe from the support 26 and mount another last with a drafted and

85 pulled-over shoe on such support. It would be desirable to swing the support 26 to the inclined position prior to removing the last

therefrom, in order to close communication with the source of supply. Each heated

90 shoe, with the last therein, would be ready for the lasting operation as soon as it is removed from the heating device.

Although both lasts shown are provided with ducts arranged to emit a heating medi-

95 um into the toe portion of a shoe, the latter portion may nevertheless be heated externally while being heated internally, and I have therefore included a toe steamer in

100 Figs. 5 and 6 to illustrate a desirable combination of the two heating devices. The toe steamer is represented conventionally at 40.

Its details of construction are not of special importance for present purposes, and it will be sufficient to state that this device has a

105 chamber into which the toe portion of a pulled-over shoe may be inserted as shown by Fig. 5, and that it comprises a steam

110 casing into which steam may be conducted and from which it may be emitted adjacent the shoe. As shown by Fig. 5, communica-

115 tion between the toe steamer and the supply pipe 28 is provided by a connecting pipe 41.

A valve is indicated at 42. In order to simplify the work of the laster as much as

120 possible, the valve 42 is connected with the last-supporting member 26 in such manner as to utilize the angular movement of the latter to operate the valve. For this purpose

the stem of the valve is provided with an operating arm 43. This arm is connected with the member 26 by a link 44 and cou-

pling device 45. It is not necessary to completely close communication between the

125 supply pipe 28 and the toe steamer when the shoe is removed from the latter, but it is desirable, at least, to reduce the volume

of steam that is being fed at such time. The

- valve 42 may therefore be adjusted to afford a relatively slight passageway for steam when the link 44 is moved to the right from the position shown, in which case there would be a relatively small flow of steam when the supporting member 26 is inclined to the right, and a relatively large flow when the supporting member is in its upright position. Whenever it is desired to close all communication between the toe steamer and the supply pipe 28, the shut-off valve 46 may be closed. The pipe connection between the supply pipe 28 and the pipe 30 is provided with a shut-off valve 47.
- In order to compensate for the difference in the length of lasts, when using the internal heating apparatus in conjunction with a toe steamer, it is necessary to adjust one relatively to the other. So far as the principle of combination is concerned, it would not matter which one were fixed and which one were adjustable, but I have shown the toe steamer as being the fixed element, and the internal heating apparatus as being the adjustable element. The block 31 is capable of movement toward and from the toe steamer for this purpose, and the bench 32 is provided with guides 48 in which the block is adapted to slide. In order to make allowance for such movement of the block relatively to the supply pipe 28, the flexible pipe 29 hereinbefore mentioned is used to conduct the heating medium to the pipe 30. Pipe 30, being carried by block 31, has movement relatively to the bench, and consequently the bench is provided with a slot 49 (Fig. 5) in which the pipe may move. The device indicated at 50 is affixed to one of the guides 48 and is adapted to coact with the sliding block to lock the latter in any desired position of adjustment. For this purpose the block is provided with a series of sockets 51, and the device 50 is provided with a bolt 52 adapted to enter any one of said sockets. As shown by Fig. 6 the right-hand end of bolt 52 is in one of the sockets. The left-hand end of the bolt is provided with a head whereby it may be withdrawn to free the block for adjusting.
- Shifting the block 31 would affect the adjustment of valve 42, in the absence of some compensatory adjustment, and for this reason the link 44 is provided with a series of holes 53, any one of which is available for connection with the operating arm 43 of the valve. As shown by Fig. 11 the arm 43 is provided with a stud 54 extending through one of the holes in the link, and provided with a thumb-nut 55 to keep the link on the stud. The holes in the link correspond to the holes 51 in the block, and when the desired position of the block has been determined, the corresponding position of the link relatively to the arm 43

may be obtained by unscrewing the nut 55, slipping the link from the stud 54, placing the stud in the desired hole 53, and replacing the nut.

The coupling device 45 that connects the link with the last-supporting member 26 is capable of adjustment toward and from the axis of the swing joint, and is therefore adapted to impart more or less motion to the valve arm 43. This coupling device comprises a metal strip formed to embrace the member 26 and having substantially parallel extremities. (See Fig. 10). One end of the link 44 is disposed between such extremities and is pivotally connected to them by the shank of a screw 56. A nut 57 coacts with the screw 56 to clamp the devices to the member 26, and the clamping strip is so formed as to clamp the member 26 without clamping the link. The screw thus acts as a pivotal connection for the link in addition to acting as a clamping device.

Although I have described the structure of the last and other apparatus as though a heating fluid were to be used, the term "heating" is not intended to have a limiting effect so far as the last is concerned, for, as explained at the beginning of the specification, the last is capable of having a stiffening fluid fed through it. The metal element 16 that is embedded in the counter portion of the last has a considerable area exposed for contact with the shoe elements, and when a heating fluid is used this metal element has a heating effect upon the counter portion of the shoe in addition to the heating effect of the heating medium that is emitted from it.

While emission of steam would probably be the most efficient way to utilize heat for the purpose of the present invention, it might not be desirable to use steam when operating upon ladies' slippers that are made of light-colored materials, such as satin, suede, or kid. In such cases steam might have a discoloring effect upon the outer material. In a great many factories a supply of heated air might not be available, and for this reason some other form of heating device could be substituted, to advantage, for the heating devices 16 and 24. For example, it would be possible to substitute electric heating coils for the heating devices 16 and 24, and in such case the connection with the source of current could be made by a contact plug designed to go into the jackpost cavity. A last so equipped would have the advantage of utilizing dry heat without any special piping in the building, for every modern factory is supposed to be wired for electric lights and for other electric apparatus.

I claim:

1. A wood last having the usual jackpost

- cavity in its heel-part, and a duct extending from said jackpost cavity to an extremity of the last.
2. A wood last having the usual jackpost cavity in its heel-part, and ducts extending from said jackpost cavity to both extremities of the last.
3. A last having a fluid-transmitting duct extending therethrough from its heel portion to its toe end.
4. A last having a cavity in its heel portion, and a duct extending therethrough from said cavity to the surface of the toe portion.
5. A last having a U-shaped conduit embedded in its counter portion and arranged adjacent and substantially parallel to the pulling-over edge of the heel portion, the latter portion having a jackpost cavity, and one or more ducts forming communication between said cavity and said U-shaped conduit.
6. A hinged last comprising a heel-part and a forepart pivotally connected together, a cavity in the heel-part, and a separable conduit extending from said cavity into the forepart for the passage of a heating medium.
7. A two-part last comprising a forepart, a heel-part, and jointed means connecting said parts and affording relative movement thereof, said heel-part having a cavity and a duct extending from the latter to the front face of said heel-part, said forepart having a duct extending from its rear face to another face thereof, said ducts being arranged to register with each other in end-to-end relation when said parts are in co-operative relation for lasting.
8. A two-part last comprising a forepart, a heel-part, jointed means connecting said parts and affording relative movement thereof, said heel-part having a jackpost cavity and a duct extending from the latter to the front face of said heel-part, said forepart having a duct extending from its rear face to another face thereof, said ducts being arranged to register in end-to-end relation when said parts are in co-operative relation for lasting, and two tubular members arranged in said ducts respectively and arranged so that an end portion of one of them will move into and out of an end portion of the other as said parts are moved to and from co-operative relation.
9. In combination, a last having a cavity in its heel portion, and a support having a portion adapted to go into said cavity, said support having a duct arranged to feed a fluid into said cavity, and said last having a duct in communication with said cavity and arranged to emit such fluid into a shoe on said last.
10. In combination, a last having a cavity in its heel portion, and a pipe having a portion adapted to go into said cavity to feed a fluid thereto, said last having a duct in communication with said cavity and arranged to emit such fluid into the toe portion of a shoe on said last.
11. In combination, a last having a cavity in its heel portion, and a pipe having a portion adapted to go into said cavity to feed a fluid thereto, said last having a duct extending from said cavity to the counter portion and having an outlet arranged to emit such fluid into the counter portion of a shoe on said last.
12. In combination, a last having a jackpost cavity in its heel portion, and a support comprising two pipe-joint members one of which is adapted to turn on the other, and a pipe one end of which is coupled to the said one of said members, the other end of said pipe being adapted to go into said cavity to hold said last, said pipe-joint members having ports arranged to be moved into and out of register with each other by such turning, to open and close communication through them, said last having a duct arranged to emit fluid from said cavity into a shoe on the last.
13. In combination, a last having a bushing in its heel portion, two co-operative pipe-joint members, and a pipe one end of which is coupled to one of said members and the other end of which has an externally tapering portion adapted to fit tightly in the mouth of said bushing, said pipe-joint members having co-operative ports adapted to feed fluid into said pipe, said one of said members being adapted to turn on the other to unregister said ports, said last having a duct arranged to emit fluid from the cavity of said bushing into a shoe on the last.
14. In combination, a toe steamer and pipe arranged to feed steam thereto, a last having a jackpost cavity, a movable member having a tubular portion adapted to go into said cavity to support said last and to feed a fluid into said cavity, said last having a duct in communication with said cavity and arranged to emit such fluid into a shoe upper arranged on said last, said supporting member being movable to carry the last to and from co-operative position relatively to said toe steamer, a feed conduit connected to said supporting member to feed such fluid thereto, a valve arranged to control the feeding of such fluid through said conduit, said valve being connected to said supporting member to be operated by movement of the latter, a valve arranged to control the flow of steam through said steam pipe, and means arranged to transmit motion from said supporting member to operate the latter said valve.
15. In combination, a last, a movable support therefor, means for supplying heat to said last while the latter is on said support,

and means controlled by movement of said support to control the supply of heat.

16. In combination, a last having a cavity, a movable tubular support adapted to project into said cavity, means connected to said support and to a source of fluid to feed such fluid through said support and into the last, said last having a duct in communication with said cavity to emit such fluid into a shoe on the last, and means operable by movement of said support to control the supply of such fluid through said support.

17. In combination, a last, a movable support therefor, means for applying heat to the last, and a controller set to cut off the heat when said support is retracted from a predetermined operative position.

18. The herein-described method of preparing a shoe upper for lasting, which consists in feeding a softening fluid into the upper while it and an insole are assembled on a last.

19. The herein-described method of preparing a shoe upper for lasting, which consists in feeding a heated fluid into the up-

per while the latter is pulled over upon a last and insole.

20. The herein-described method of preparing a shoe upper for lasting, which consists in assembling the upper and an insole upon a last that has a duct extending through it, and feeding a heated fluid into the upper through such duct.

21. The herein-described method of softening a stiffening member of a shoe upper, which consists in placing such upper, with such stiffening member therein, upon a last that has a duct extending through it to a point contiguous to such stiffening member, and feeding a heated fluid through such duct to such stiffening member.

22. The herein-described method of treating an absorbent stiffening member of a shoe upper, which consists in feeding a fluid substance to such stiffening member through the interior of the shoe while the latter is upon a last.

In testimony whereof I have affixed my signature.

WILLIAM A. STUBBS.
